(57) **CLAIM**

The ornamental design for a light fixture lens end, as shown and described.

DESCRIPTION

FIG. 1 is a bottom perspective view of a light fixture lens end of the present invention;

FIG. 2 is an end elevational view of the light fixture lens end of FIG. 1;

FIG. 3 is a bottom plan view of the light fixture lens end of FIG. 1;

FIG. 4 is a side elevational view of the light fixture lens end of FIG. 1;

FIG. 5 is a bottom perspective view of a second embodiment of a light fixture lens end of the present invention;

FIG. 6 is an end elevational view of the light fixture lens end of FIG. 5;

FIG. 7 is a bottom plan view of the light fixture lens end of FIG. 5;

FIG. 8 is a side elevational view of the light fixture lens end of FIG. 5;

FIG. 9 is a bottom perspective view of a third embodiment of a light fixture lens end of the present invention;

FIG. 10 is an end elevational view of the light fixture lens end of FIG. 9;

FIG. 11 is a bottom plan view of the light fixture lens end of FIG. 9;

FIG. 12 is a side elevational view of the light fixture lens end of FIG. 9;

FIG. 13 is a bottom perspective view of a fourth embodiment of a light fixture lens end of the present invention;

FIG. 14 is an end elevational view of the light fixture lens end of FIG. 13;

FIG. 15 is a bottom elevation view of the light fixture lens end of FIG. 13; and,

FIG. 16 is a side plan view of the light fixture lens end of FIG. 13.

The broken lines adjacent the shaded areas represent the bounds of the claim and all other broken lines are for illustrative purposes only. None of the broken lines form part of the claimed design. The top of each embodiment of the lighting fixture lens end is not visible during normal use and also forms no part of our claimed design.
